UNITED STATES PATENT OFFICE.

CHARLES G. CAMPBELL, OF CHICAGO, ILLINOIS, ASSIGNOR TO KEWAUNEE MFG. CO., OF KEWAUNEE, WISCONSIN, A CORPORATION OF WISCONSIN.

TABLE-TOP.

1,276,719.

Specification of Letters Patent. Patented Aug. 27, 1918.

Application filed December 17, 1917. Serial No. 207,492.

To all whom it may concern:

Be it known that I, CHARLES G. CAMPBELL, a citizen of the United States, and a resident of the city of Chicago, county of 5 Cook, and State of Illinois, have invented certain new and useful Improvements in Table-Tops, of which the following is a specification.

My invention relates to improvements in 10 table tops especially adapted for laboratory tables and the like, and has for its object the provision of an improved construction of this character which will not warp, and in which the seams will not open in use.

15 The invention consists in the combinations and arrangements of parts hereinafter described and claimed.

The invention will be best understood by reference to the accompanying drawings 20 forming a part of this specification, and in which,

Figure 1 is a perspective view of a table equipped with a top embodying the invention,

25 Fig. 2, an enlarged section taken on line 2—2 of Fig. 1,

Fig. 3, an enlarged transverse section taken through the central portion of the table top at right angles to Fig. 2,

30 Fig. 4, a detail view of a portion of one edge of the table top, and

Fig. 5, a detail section illustrating the mounting of one end of a plurality of binding rods employed in the construction.

35 The preferred form of construction as illustrated in the drawings comprises a table top made up of a plurality of tongued and grooved strips or boards 6, arranged adjoining each other to constitute the table

40 top in the usual manner. A sink opening 7 is provided centrally in said table top and a sink 8 of any usual or ordinary construction is arranged under said sink opening, suitable water faucets 9 being arranged 45 to discharge into said sink.

Transversely alining openings 10 are provided in the table top strips or boards 6, one of said openings being provided at each side of the sink opening 7 and adjacent the 50 ends of the strips, and binding rods 11 are passed loosely through said openings 10. Recesses 12 are provided in the outermost table top boards or strips surrounding the ends of the rods 11 and compression springs 55 13 are arranged in said recesses on the cor-

responding rod ends between suitable washers as shown. Nuts 14 are threaded on the ends of the rods to serve as a means of adjusting the tensions of said springs and for drawing the table top strips or boards 60 tightly together. Plugs 15 are inserted in the outer ends of recesses 12 to present a smooth surface and protect and conceal the inclosed parts.

By this arrangement it will be observed 65 that the binding rods 11 being arranged to move freely in their openings, the strips 6 are of course equally free to move on the rods, so that said strips may expand and contract under varying weather or other 70 conditions without compelling movements of the rods. Likewise the spring at each end of the rod provides for expansions and contractions of the boards or strips at the corresponding side of the table without affecting the relations of the rods in the other side of the table. This arrangement 75 is especially advantageous at the edges of the sink openings where movements of the rod would tend to open the seams or joints 80 in the table top and to disseminate moisture through the openings 10 to the different boards or strips in the table top.

While I have illustrated and described 85 the preferred form of construction for carrying my invention into effect, this is capable of variation and modification without departing from the spirit of the invention. I, therefore, do not wish to be limited to the precise details of construction set forth, 90 but desire to avail myself of such variations and modifications as come within the scope of the appended claims.

Having described my invention what I 95 claim as new and desire to secure by Letters Patent is:

1. A table top comprising a plurality of adjoining strips, there being a sink opening formed through said table top and alining openings in said strips at each side 100 of said sink opening; binding rods extending through said openings, said rods being somewhat smaller than said openings and freely movable therein; and a yieldable bearing at each end of said rods bearing 105 against the corresponding outermost strip, substantially as described.

2. A table top comprising a plurality of adjoining strips, there being a sink opening formed through said table top and alining 110

openings in said strips at each side of said sink opening; binding rods extending through said openings, said rods being somewhat smaller than said openings and freely movable therein; and a compression spring at each end of said rods bearing against the corresponding outermost strip, substantially as described.

In testimony whereof I have signed my name to this specification in the presence of 10 two subscribing witnesses.

CHARLES G. CAMPBELL.
